UNITED STATES PATENT OFFICE.

GEORGE MESSIG, OF BROOKLYN, NEW YORK.

TUNE-SHEET-PERFORATING DEVICE.

Application filed January 3, 1921. Serial No. 434,745.

To all whom it may concern:

Be it known that I, GEORGE MESSIG, a citizen of the United States, and resident of Brooklyn, in the county of Kings and State 5 of New York, have invented a certain new and useful Tune-Sheet-Perforating Device, of which the following is a specification, the same being a full, clear, and exact description of the invention, such as will enable 10 others skilled in the art to which it appertains to make and use the same.

This invention relates to the production and embellishment of tune sheets such as are used in automatically played instruments 15 and other devices for reproducing sounds in such manner that the perforations formed shall correspond to the notes to be played, and it has for its object the improvement of machines of this character in numerous im- 20 portant respects.

One special object of the invention is to provide supplemental perforations in tune sheets representing expression, augmentation 25 of power, change of speed, or auxiliary music producing instruments such as bells, cymbals, triangles, etc., and intended to denote notes which are to be played in various ways and operated by a pneumatically actuated instrument.

30 My sheet marking apparatus is ordinarily and preferably employed in connection with the usual tune records having marginal side portions, the supplemental perforations being made preferably at each side of the rows 35 of orifices or marks of such ordinary tune sheets and inserted in their proper place as the music is being heard, the former perforations representing expression, etc., thus serving as companion records to the orifices 40 contained in the body portion of the said tune sheet.

In the practice of my invention I preferably use the mechanism ordinarily employed in pneumatically operated instruments 45 in which the ordinary perforated tune sheet is passed across the tracker bar, and I combine with the same a manually actuated and preferably detachable apparatus by means of which supplemental perforations— 50 preferably approximately aligned with the tracker bar—may be cut in the said record by the depression of certain keys according to the theme of the music and the discretion or taste of the operator; the number or va-

riety of the perforations to be cut depending 55 upon the number of auxiliary music producing instruments or devices to be employed, and the proper time and extent to which the same are to be introduced, and also upon the nature of the music produced by the instrument tune sheet.

I provide a plurality of dies or a bed- 60 die either integrally incorporated in the ori- fices at each side of the tracker bar, or else positioned at each end and in alignment 65 with a shortened tracker bar, as the provi- sion of a structurally independent mech- anism. I also use in connection with the 70 said dies a series of punches preferably op- erated seratim by striker bars, each of which is actuated by the depression of its par- ticular key.

In order to attain rapidity of operation I preferably employ, in connection with 75 such punches and striker bars, electromag- nets each of which is energized by the com- pletion of its circuit upon the depression of the said corresponding key.

I prefer to arrange the parts so that the 80 supplemental perforations will be positioned slightly ahead or forward of the correspond- 85 ing orifices of the tune sheet as it passes across the tracker bar in order to represent staccato notes so as to add brilliancy and life or sharpness to the music produced, espe- 90 cially where the said supplemental perforations serve to cause drums, castanets, xylo- phones, etc., to be operated.

By my invention I am able to take the 95 ordinary tune sheet as now used with player pianos, organs and similar pneumatically operated instruments, and at a small cost to equip the said records with supplemental perforations by means of which notes repre- 100 senting expression, augmentation of power, change of speed, the singing of birds, or the actuation of a great variety of music pro- 105 ducing instruments may be added thereto, thus materially enhancing the value of the same.

With the above, and other novel and desir- 110 able purposes described herein, in view, the invention consists in the construction, ar- rangement and operation of parts set forth, the whole being combined in an organiza- 115 tion, comparatively simple in construction, reliable in operation and efficient in practical use.

In the drawings, illustrative of one embodiment of the invention, which accompany and form a part of this specification—

Figure 1 represents a perspective view of 5 an instrument equipped with my invention;

Figure 2 is an elevation of my perforation cutting apparatus;

Figure 3 is a side elevation of my electro-mechanical machine showing the punch operating device, and taken on the line III—III, Figure 2;

Figure 4 is a partial elevation of my tune sheet;

Figure 5 is a view in detail, partly in section taken on the line V—V, Figure 3;

Figure 6 is a front view of the die block, and

Figure 7 is a front view in detail of the standards of my detachable frame.

20 Referring specifically to the drawings, the numeral 1 denotes the frame of my perforation cutting machine which may be applied to any of the usual pneumatically operated musical instruments having sheet supporting rolls, means to operate the same, and in which a tracker bar 2 is employed. My device is provided with dies 5 which may either be of the ordinary bed-die form or of separate and independent construction; in the 30 latter case the individual dies may be inserted in the orifices at the end portions of the tracker bar in the usual manner of mounting dies.

35 In the present instance I show die blocks 3 which are so constructed and arranged relative to the preferably detachable machine and the tracker bar of the musical instrument that, when the frame is positioned on the former, engaging devices, as 40 a pin 21, will engage corresponding sockets in the said musical instrument in such a manner that a space 7 will be formed in which the tune sheet 8 may travel as it passes by or across the orifices 6 of the 45 tracker bar.

The frame 1 carries a series of punches 4 constructed and arranged to register with and, upon being manipulated, to enter the said dies thereby cutting or perforating the 50 tune sheet. These punches may be directly operated by striker bars 19 which may be actuated by the armatures of any desired number of electromagnets 17 each of which is energized by the completion of the circuit in which it is located, as by the contact with the key 11 with an insulated plate 12, the said elements being respectively connected with wires 13, 14 and 15 as indicated in the drawings, the said wires being carried to their respective electromagnets by a cord 16 in the ordinary manner.

55 I preferably construct the electromagnet armature 18 and its connections so that a make-and-break contact or vibratory action 60 will be automatically effected when the said

magnet is energized whereby the said armature and connected striker bar, and consequently its punch, will be rapidly reciprocated, and whereby a long perforation or slot will be cut in the paper when the key is 70 held depressed for a period of time, the said parts being normally held in inoperative position by springs 18'. Upon a quick stroke of the key the ordinary supplemental perforation 10 will be cut.

75 The aligned die blocks 3—which even if they comprise individual dies may be regarded as bed-dies—are preferably located at the side walls of my machine so as to more readily perforate the side edges of the 80 tune sheet, and the parts are preferably so arranged that the said orifices will be cut ahead or in advance of the perforations 9 formed in the body of the tune sheet, in order that there may be no danger of any 85 lagging behind of the sound of the auxiliary music producing devices from the note of the tune sheet with which it is to be combined.

90 The numeral 20 denotes a receptacle made in channel form and open at the top and extending under the tracker bar and constructed and arranged to receive the punchings formed during the operation of the machine. The punchings which collect in this 95 open receptacle may be driven out by means of a blast or exhaust, suitable connections (not shown) being provided for this purpose.

100 The tune sheet shown in Figure 4 may be used where the expression orifices 10 are cut so as to lie slightly in advance of the music note perforations 9 of the tune sheet, which latter is to be employed in instruments where all of the orifices of the tracker 105 bar are in alignment, and where each expression orifice 10 will cause the instrument to be actuated before it becomes affected by its corresponding music perforation or slot 9.

110 I, sometimes, however, arrange my perforation cutting machine so as to cut the said expression orifices in the tune sheet so as to be in alignment with the corresponding music note perforations in the said 115 sheet, in which case the expression orifices, as 5, located in the tracker bar 2 may be positioned in advance of the music note perforations, as 6, of the said tracker bar, as indicated in Figure 6, in order that the expression orifices of the tune sheet will cause the instrument to be actuated before it is affected by the music notes of the said sheet, even if the said expression and music note 120 perforations are aligned in the tune sheet. 125

130 It will be noted that I provide a perforating attachment for the tune sheet 8 of instruments having music rolls consisting of a detachable frame 1 comprising a series of manually actuated keys 11 and a series of 135

- 5 punches arranged to be respectively actuated by the various keys and constructed and arranged upon the said keys being actuated to cut expression perforations 9 in the traveling perforated tune sheet of the said instrument. The latter is provided with a number of auxiliary instrumentalities and the said expression perforations are adapted to control the playing of the various auxiliary 10 musical instruments in harmony with the perforations 10 of the traveling tune sheet. I wish it to be understood that I do not desire to be limited to the particular use or the exact details of construction shown and 15 described, for obvious modifications will occur to persons skilled in the art.
- What I claim as my invention is:—
1. Apparatus comprising an ordinary perforated tune sheet, supporting rolls and a 20 tracker bar therefor, and means to draw the sheet across the latter, in combination with a detachable frame having a plurality of dies adjacent to and at one end of the tracker bar, a series of punches to co-operate with the dies to cut expression perforations in the tune sheet and a manually actuated device to operate each punch, the said expression perforations being adapted to control the playing of various auxiliary 25 musical instruments in harmony with the perforations of the traveling tune sheet.
  2. Apparatus comprising an ordinary perforated tune sheet, supporting rolls and a tracker bar therefor, and means to draw the sheet across the latter, in combination with a detachable frame having a plurality of dies positioned slightly in advance of and at one end of the tracker bar, a series of punches to co-operate with the dies to cut expression perforations in the tune sheet, and a manually actuated device to operate each punch.
  3. Apparatus comprising an ordinary perforated tune sheet, supporting rolls and a tracker bar therefor, and means to draw the sheet across the latter in combination with a detachable frame having a plurality of dies positioned slightly in advance of and at one end of the tracker bar, a series of punches to co-operate with the dies to cut expression perforations in the tune sheet, an electromagnet to actuate each punch, and a manually actuated device to complete the circuit of each electromagnet.
  4. Apparatus comprising an ordinary perforated tune sheet, supporting rolls and a tracker bar therefor, and means to draw the sheet across the latter, in combination with a detachable frame having a manually actuated instrument to cut supplemental expression perforations in the tune sheet in approximate alignment with each row of corresponding orifices in the said tune sheet.
  5. Apparatus comprising an ordinary perforated tune sheet, supporting rolls and a tracker bar therefor, in combination with a manually actuated series of dies positioned slightly in advance of the tracker bar to cut supplemental expression perforations in the tune sheet adapted to control the playing of various auxiliary musical instruments in harmony with the perforations of the traveling tune sheet.
  6. In apparatus comprising an instrument having music producing elements and an ordinary perforated tune sheet, supporting rolls and a tracker bar co-operating with and controlled by the perforations, in combination with a separate frame having a manually actuated series of devices adjacent to the tracker bar to cut, in addition to and at lines at the side of the said perforations, supplemental expression perforations in the tune sheet adapted to control the playing of various musical instruments in harmony with the operation of the music producing elements of the instruments controlled by the said perforations of the traveling tune sheet.
  7. Apparatus comprising an ordinary perforated tune sheet, supporting rolls and a tracker bar therefor, and means to draw the sheet across the latter, in combination with a detachable frame having an electrically controlled and manually actuated instrument to cut supplemental expression perforations in the tune sheet in alignment with each row of corresponding orifices in the said tune sheet.
  8. Apparatus comprising an ordinary perforated tune sheet, supporting rolls and a tracker bar therefor, means to draw the tune sheet across the tracker bar, in combination with a detachable frame having electrically controlled manually actuated punches to cut supplemental expression perforations in the tune sheet the said punches lying slightly in advance of each row of corresponding orifices in the said tune sheet.
  9. Apparatus comprising an ordinary perforated tune sheet, supporting rolls and a tracker bar therefor, means to draw the tune sheet across the tracker bar, in combination with a detachable device comprising a series of punches positioned adjacent to and at one end of the tracker bar, and a manually actuated device to operate each punch, and also a plurality of intermediate electromagnets and means for energizing each of the same by the depression of its corresponding manually actuated device.
  10. Apparatus comprising an ordinary perforated tune sheet, supporting rolls and a tracker bar therefor, means to draw the tune sheet across the tracker bar, a detachable device having a plurality of dies positioned slightly in advance of and at one end of the tracker bar, a series of punches to co-operate with the dies, an electromagnet to actuate each punch, a spring to hold each punch

away from the tune sheet, a striker bar intermediate each electromagnet and punch, and a manually actuated device to complete the circuit of each electromagnet.

5 11. Apparatus comprising an ordinary perforated tune sheet, supporting rolls and a tracker bar therefore, in combination with a plurality of dies at one end of the tracker bar, a series of punches to co-operate with 10 the dies, and a manually actuated device to operate each punch to cut expression perforations in the margin of the tune sheet,

the punches and dies and the music note orifices being so relatively positioned that when the tune sheet passes across the tracker 15 bar, the expression perforations will communicate with the tracker bar, before the music note perforations of the said tune sheet.

Signed at Brooklyn in the county of Kings 20 and State of New York this 22nd day of December A. D. 1920.

GEORGE MESSIG.
